UNITED STATES PATENT OFFICE.

CESIDIO SERO, OF CARNEYVILLE, WYOMING.

CAR-DOOR.

1,277,651.

Specification of Letters Patent. Patented Sept. 3, 1918.

Application filed July 28, 1917. Serial No. 183,243.

To all whom it may concern:

Be it known that I, CESIDIO SERO, a subject of the King of Italy, residing at Carneyville, in the county of Sheridan and State 5 of Wyoming, have invented certain new and useful Improvements in Car-Doors, of which the following is a specification.

This invention relates to an improvement in car doors, and particularly to an auxiliary 10 door adapted to be fitted for use upon box and other like cars to adapt the same for expeditious handling and shipping of grain, coal, and the like.

An object of my invention is to provide 15 a structure which can be built into a car when the same is constructed in the shop, or which can be fitted to cars already in use, the structure being such that it is not necessary to remove the usual sliding door or 20 to otherwise greatly alter or reconstruct the standard construction of cars.

A further object lies in constructing parts 25 in such a way that when the car is to be unloaded, the door structure can be folded and swung out from the doorway of the car and can be moved around to rest against the outer side of the sliding door, thus being located at such a point that loading or unloading of the cars will not be interfered 30 with, and which structure has the parts thereof so hinged together that they can be folded to be swung inside of the car and to be received entirely within a pocket or recess provided on the inner wall of the car by 35 leaving out a section of the lining as ordinarily employed, in which position of the parts the door will not offer any material protrusion from the wall lines of the car.

A still further object resides in providing 40 means by which the several sections of the door are braced one against the other and by which the door structure will be braced and held as substantially a continuous structure, when in use; together with bracing structure 45 adapted for attachment to the door structure and for engagement with the car frame to thus rigidly mount the door against displacement from the door opening and to present substantially a continuation of the 50 car side.

With the above and other objects in view, which will be in part described and in part understood from the specification, drawings, and claims, my invention consists in

certain novel features of construction and 55 combinations of parts which will be herein-after more fully set forth.

In the drawings:

Figure 1 is a partial view of one side of a car showing my improved door fitted thereto 60 and in use;

Fig. 2 is a view similar to Fig. 1 but showing the door opened out;

Fig. 3 is a view taken from the inner side 65 of the car and showing the parts as they are disclosed in Fig. 1;

Fig. 4 is a view similar to Fig. 3 but showing the door folded into a recess in the wall 70 of the car and in the position it will occupy when not in use;

Fig. 5 is a sectional view taken on the line 5-5 of Fig. 3;

Fig. 6 is a horizontal sectional view taken on the line 6-6 of Fig. 4; and,

Fig. 7 is a horizontal sectional view on the 75 line 7-7 of Fig. 2, and looking in the direction indicated by the arrow.

As has been stated, the door structure, 80 constructed after the manner of my invention, can be fitted for use in conjunction with box cars, or cars of other types, and in the present instance where I have shown the door as applied to a box car, the parts are for the most part, substantially without change from standard construction. The 85 side wall 1 of the car has the door opening 2 provided therethrough, and a sliding door 3 operating on a track 4, is provided to close the opening 2. To all intents and purposes, the car construction is substantially standard, with the exception that at one side of the door opening 2, the inner lining or wall 5, as now ordinarily used in car construction, is in part omitted so that a recess or 90 pocket is provided as shown at 6.

The improved door structure which is 95 made up of wood, metal, or a combination in which wood is reinforced by the use of metal, comprises the rather narrow sections or slats 7, 8, and 9, which are foldably connected together by means of hinges as indicated at 10 and 11, and a relatively wider section or panel 12, which is mounted upon the outer edge of the section 9, by means of 100 hinges 13, this panel 12 being thus foldably connected to be swung back against the slats 7, 8, and 9. Hinges 14 are connected with the door section 7 and then by use of bolts 105

15, or other suitable fastenings, the entire door structure is mounted in place upon the car structure to swing upon the hinges 14. The hinges 14 mount the door structure at 5 one side of the recess or pocket 6 on the inner side of the car wall, and the width of this recess or pocket is sufficiently great that when the door section 12 is swung back against the sections 7, 8, and 9, and the entire 10 tire structure is moved in a swinging path upon hinges 14, the folded door structure as an entirety will be received in this pocket or recess 6, in which relation the parts are held against return movement by means of 15 a spring latch 16 which is carried by the car structure. Through the fact that the hinges 10 and 11 by which the sections 7, 8, and 9, are connected together are disposed to be on the outside when the parts are swung 20 into the recess, and that these hinges are of the single acting type, or are adapted to swing in only one direction, this spring latch 16 will hold the door structure against displacement from the recess and closing or extension of any of the parts therefrom will 25 not be permitted, thus making the door structure conform substantially to the lines of the inner walls, and giving to all intents and purposes a substantially continuous and 30 unbroken car wall.

The construction of the inner portion of door to comprise the sections 7, 8, and 9 permits the structure to be swung out, through the fact that the slats will fold around the 35 door post, while the main panel of the door will be swung to be entirely outside of the car and to rest and bear against the outer side of the sliding door 3, this setting of the parts being shown in Figs. 2 and 7. To provide for securing the door structure in this 40 full opened relation, hooks 17 are carried by the free end of the panel 12 and eyes 18 are provided on the door 3, to which the hooks may be fitted.

45 From the foregoing it will be seen that the door sections are more or less flexibly connected together and as considerable weight is placed upon the door structure when the car has grain, coal, or other commodities loaded thereinto, it is natural that the car door will be forced and bulged out when it is brought to the closed position, unless braced and rigidly held in place. With this purpose in view, I provide an inside 50 brace member 19, which is adapted to be placed across the hinge joint, between sections 9 and 12 of the door and to be rigidly secured in place thereon by the use of bolts 20, it of course being understood that in view of the fact that the hinges 10 and 11 55 are placed on the outer sides of the sections 7, 8, and 9, as these parts are set in closing the door, bulging of these sections outwardly is not permitted. The mounting of 60 inside brace bar 19 will act to very mate-

rially stiffen and hold the door sections, and while the hinges 10 and 11 will restrain the sections 7, 8, and 9, against bulging, it is preferable that additional bracing be introduced to reinforce the stiffening accomplished by brace 19, and also that bracing be provided to relieve the strain upon the hinges 10 and 11, and this can be accomplished by bars placed on the outer side of the door. With these purposes in view, I 70 provide openings 21 and 22 in the inner side edge and the sill respectively of the door framing, and provide a relatively wide bar or plate 23 which has a brace bar 24, pivoted thereon by means of pin 25. This plate 23 75 has bolt receiving openings through the upper end thereof and the bolts 20, by which the inside brace bar 19 is mounted in place, or other suitable bolts are used in rigidly mounting this plate 23 upon the door sections, it being preferable that fastening be accomplished to secure the bar or plate 23 to the section 9 and also to the section 12. 80

This will maintain the outside bracing members in a rigidly mounted position in 90 the keeper slots or openings 22 and 21 respectively, and thus when the plate and bar are secured in place these members will be locked against accidental or casual displacement from the keeper slots or openings, and 95 at the same time will be positively held in such relation that they reinforce and brace the several door sections, in this respect cooperating with inside brace bar 19. To secure the free edge of the door section 12, 100 the hooks 17 are inserted in eyes 26 carried by that door post opposite to the one on which the hinges 14 are mounted, and in this way the door structure as an entirety is braced and reinforced in its body portion and is 105 rigidly secured to the door posts at opposite sides of the door openings.

When the door is closed and secured as above set forth it will of course be understood that to open the same it will be necessary to remove the hooks 17 and the eyes 26, and to remove the bolts 20 so that the inside brace bar 19 and the outside plate 23 having the bar 24 carried thereby, can be removed and when this has been done the sections 110 have unrestrained swinging movements. If desired, pins or studs 27 and 28 can be provided on the inner sides of the slats 7 and 8, to have the inside brace member 19 and the outside plate 23 hung thereon, to retain 115 these parts against loss when the door is not in use.

As the manner of mounting and of using the door has been rather fully described as the description has progressed, it is not here 120 believed necessary to go further into the manner of use. However, attention might be called to the fact that when desired the door structure can be removed by closing the sliding door 3 and obtaining access to 125 130

the bolts 15 by which the door structure as an entirety is mounted in conjunction with the car structure.

While I have herein shown and described the various parts as being constructed in certain specified ways and as being connected in a prescribed manner, it will be appreciated that variations might be made in the materials used, in the manner of constructing the parts, the manner of mounting the same for use, and in other structural and assembly features, and hence I wish to be limited only to such points as may be set forth in the claims.

I claim:

1. In a car door structure, the combination with the car wall having a door opening with posts at opposite sides thereof, and a recess adjacent one post, there being an opening in said post and an opening in the sill; of a door made in sections hingedly connected with each other and hinged to said post so as to fold into said recess or to unfold and extend across the door opening, a plate removably seated in the opening in the sill and rising alongside the door when distended, means for removably securing it to said door, and a brace bar connected with the plate at one end and with its other end seated in the opening in said post.
2. In a car door structure, the combination with the car wall having a door opening with posts at opposite sides thereof, and a recess adjacent one post, there being an

opening in said post and an opening in the sill; of a door made in sections hingedly connected with each other and hinged to said post so as to fold into said recess or to unfold and extend across the door opening, an upright brace element seated at its lower end in the opening in the sill, a horizontal brace element seated at one end in the opening in the post and connected at its other end with the first-named element, and bolts passing through this brace structure and certain of said door sections, for the purpose set forth.

3. In a car door, the combination with a wall structure having spaced posts at opposite sides of a door opening and a recess in the sill of the latter; of a door made in sections hingedly connected with each other and one endmost section hingedly connected with one post, an upright brace element mounted at its lower end in said recess and standing outside the door across the hinge line between two of its sections, a horizontal brace element standing inside the door and crossing a plurality of hinge lines, and bolts removably passing through both elements and the interposed sections, for the purpose set forth.

In testimony whereof I affix my signature in presence of two witnesses.

CESIDIO SERO.
